UNITED STATES PATENT OFFICE

EPHRIAM D. PONDER, OF GAINESVILLE, FLORIDA

MULTIPLE VACUUM ACTION PIPE ORGAN

Application filed August 3, 1931. Serial No. 554,874.

This invention relates to organs and particularly to pipe organs having a pressure wind chest for causing the pipes to speak and a vacuum chest for causing the operation of the means for controlling the valves from the pressure chest to the pipes.

The primary object of this invention is the production of a simplified pipe organ.

Another object of the invention is the provision of a pressure tension chest for supplying the pressure for the speaking pipes and a vacuum tension chest close to the pressure chest for providing the tension for the device which operates the pressure valves controlling the passages to the pipes.

Still another object of the invention is the provision of means for causing, at will, the simultaneous speaking of pipes which have harmonious notes, by the operation of a single note at one end of the series.

Still another object of the invention is the provision of such an organ having stop means for controlling the speaking of any one or plurality of notes in a harmonic series and for at will connecting all of the series together for speaking.

Another and still further object of the invention is the provision of such an organ having stop means for controlling the simultaneous speaking of any one or more of the notes of a harmonic series in one row of pipes or a plurality of rows of pipes, at will, by the operation of a single key.

Another and still further object of the invention is the provision of a means whereby the air from the vacuum chest is exhausted therefrom and immediately returned to the pressure chest, thereby supplying air for speaking notes at the same temperature and humid state as the air of the room.

Another and still further object of the invention is the provision of an improved pneumatic valve box wherein the parts may be easily separated for inspection or repair and have the portions of the box hinged together to insure exact registration upon replacement.

Other and still further objects will be apparent to those skilled in the art from a reading of the complete specification and claims.

Referring to the drawings wherein I have illustrated an embodiment of the invention,

Figure 1 is an illustration of the main features of the invention, shown more or less diagrammatically to more clearly illustrate the details of construction.

Figure 2 is a cross section of the wind chest assembly showing two series of pipes and the proximity of the wind and vacuum tension chambers in the main series.

Figure 3 is a fragmental detail view of one of the check valves in a harmonic series connecting line.

Figure 4 is a cross sectional view on the line 4—4 of Figure 1.

Figure 5 is a diagrammatic showing of the wind chest and vacuum tension chest and producing means for vacuum and wind tension.

Similar reference characters refer to the same or similar parts throughout the specification and drawings.

Referring particularly to Figures 1 and 2, 20 designates generally the side boards of the wind chest which are provided at their upper edges with a top board 21 which boards 20 and 21 are provided with openings to receive the pipes 22 which are thus arranged in two rows on the top of the wind chest, an opening 23 is drilled through the boards 20 and 21 to conduct the air from a drilled valve port 24 to the pipe 22. At the port 24 is provided a valve seat 25 on which is a valve 26. The valve 26 is supported by a valve stem 27 which passes through the side board 20 and is provided at its end with a small head 27'.

To operate these valves 26, I provide power pneumatics 28 on the outside of the wind chest. A duct 29 leads from the power pneumatic to the primary pneumatic unit which controls the operation of the power pneumatic 28 and which will now be described.

The primary pneumatic unit comprises a plurality of members such as the upper member 30, the intermediate member 31 and the lower member 32. These members of the unit are hinged together in any suitable manner as by the soft leather hinge 33. The parts 30, 31 and 32 are held in place by the screws 30'. One of the members, as 30, is provided

100

with a valve chamber 34 having therein a suitable valve 35 for controlling the admission of tension to the power pneumatic 28. This valve is suitably controlled in a vertical 5 path by suitable guides and when in its upper position registers with an opening 30^a in the upper end of the valve chamber and connects the latter to atmosphere when the valve is in its lowered position.

10 One member as the member 31 is provided with a vacuum chamber 36 which is connected by the duct 37 which passes through the bottom board 38, of the wind chest, to connect with the vacuum chamber 33^a from which 15 comes the tension to operate the power pneumatic 28. At the upper end of the vacuum chamber 36 is a port 31^a which is normally closed by the lower end of the valve 35.

The valve 35 has a stem 39 which extends 20 downwardly into the chamber 36 and in position to be lifted by the primary pneumatic pouch member 40, secured to the top of the member 32 above the pouch chamber 41.

A suitable bleed connection is provided at 25 42 to connect the pouch chamber with a small hole to collapse the pouch after its operation is no longer desired. The pouch chamber 41 is connected to a duct 42 which leads to a connection duct extending to a duct opening 30 which is covered or uncovered by the operation of a key of the manual.

In the practice of my invention, it has been found to be particularly advantageous to have the vacuum chest and the wind chest in 25 close proximity to each other, in order to have the power pneumatic operated by vacuum and with as short a duct as possible.

In carrying out my invention, I have provided connections between certain of the 40 pneumatics of the same row whereby when desired, the player can by the use of a stop, so connect the connections to the power pneumatics that when a note is caused to speak, another note of the same harmonic series will 45 also speak. In this specification and the claims, the term "harmonic series" is intended to mean those notes which in the same row of pipes, will harmonize as for example major and minor chords. For example, if the 50 note F is made to speak when this stop is operated, then the note A, which is the second of that harmonic series, will also speak. If the note F[#] is sounded, the note A[#] will also sound and so on.

55 I have also provided connections whereby the first and third notes of an harmonic series may be sounded simultaneously as F and C or F[#] and C[#]. I have further provided another stop which will sound the fourth note of the 60 harmonic series when a note is sounded as when F is sounded, F-octave will sound simultaneously.

In order to further control the sounding 65 of the notes of an harmonic series, I have provided a single stop and connections where-

by the operation of the stop will cause all four of the notes of the harmonic series to be sounded simultaneously.

The numeral 50 represents the keys of the console which operate to control the playing 70 of the notes. The duct 51 having an opening 52 connects with the duct 42 already described. When a key 50 is pressed, the end of the opening 52 of the duct 51 is uncovered and air enters the duct 51 and passes to the duct 75 42 which is under the influence of the exhaust tension. The air passes along the duct 42 to the control device adjacent the wind chests. As this air impulse reaches the control devices, it has a tendency to be divided 80 into five different parts and under certain circumstances does so divide. The first part enters the pouch chamber 41 and operates the primary pneumatic 40 of the pipe corresponding to the key 50 which is operated. 85 For the sake of description of this operation, let the note to which the key 50 corresponds, be F. The other four divisions of the impulse of air through the duct 42 are distributed; three to connections to at will control individually the sounding of other notes of the harmonic series of which F is considered the first note and the other division to connections to control, simultaneously, the speaking 90 of all four of the notes of that harmonic series.

The branches to control the speaking, individually, of the notes of the harmonic series, I have designated as 42^a, 42^c and 42^f, to denote the ducts leading to the pouch chambers 41 of the primary pneumatics of the notes A, C and F-octave, respectively.

However, before the impulse of air reaches the primary pneumatic pouch it is to operate, it must pass the stop control device which 105 controls connections from each note to another note which is one of its harmonic series. For example, in the embodiment herein illustrated, each note of the series of pipes of the chromatic series of a row of pipes, is connected to the next one of its harmonic series and all of these connections are under control of a single stop. And since each pipe is connected to the corresponding pipe of every other row under control of the same manual 110 for speaking, it follows that the same simultaneous speaking of the pipe played and the speaking of the next pipe of that harmonic series will take place and will be duplicated by the corresponding pipes of any row of 115 pipes controlled by that manual if the wind control stop for that row of pipes is operated to admit air to its wind chest.

In the same way, other connections under control of a single stop, are provided to cause the third of the harmonic series to speak when the first of such series is caused to speak.

And likewise, other connections under the control of a single stop, are provided to cause the fourth note of the harmonic series which 120

is an octave higher, to speak when the first of such series is caused to speak.

It is thus seen that there are three such stops, controlling the speaking of the second, third and fourth pipes, respectively, of all the harmonic series, when the first note of any harmonic series is caused to speak. These stops operate independently of each other so that any two or all of the notes may be sounded with the first of the series, depending upon which stops are operated.

Operating independently of these three stops, is a fourth stop which puts on all of the three additional pipes of the harmonic series when the first pipe is caused to speak. This stop is so arranged that it may be operated without disturbing the setting of the other three stops. Further the return of the fourth stop to its normal "silent" position, returns the pipes to the control of the three stops which control the individual pipes of the several harmonic series. The branch duct which leads off from the duct 42, I have designated as 42^x.

Considering one of the four branches of the duct 42, as for example, the duct 42^a, one division of the pneumatic impulse passes along the duct 42^a until it reaches the chamber 53^a on one side of the diaphragm pouch 54^a. Connected to the chamber 53^a is a duct 55^a through which the impulse passes to a check valve box 56^a having a check valve 57^a in a chamber 58^a. After passing through the chamber 58^a the impulse of air passes through the duct 59^a to the primary pneumatic chamber 41 of the note A which is the second of the harmonic series of which F is the first note.

The diaphragm pouch 54^a has on its upper side, as shown, a chamber 60^a. The pouch 54^a and chamber 60^a are illustrative of a number of such pouches and chambers, there being one to correspond to the second of a harmonic series of which each of the successive pipes is the first. The chambers 60^a are all connected to a single conduit 61^a to which is connected a tube 62^a which leads to a stop member 63^a in position to be operated by the player while the latter is playing. This stop member 63^a is provided with a cut away portion 64^a which connects the opening of the duct 62^a with either the duct 65^a, leading to the wind tension chest W, or to the opening of the duct 66^a leading to the vacuum tension chest V. The wind tension and vacuum tension for the chests W and V respectively are supplied in a manner to be later described.

By pushing, the stop member 63^a inwardly or to the left as illustrated, it will be seen that the ducts 62^a and 66^a will be connected together. This will connect the duct 62^a with vacuum tension from the chest V.

This vacuum tension will pass along the duct 62^a to the chamber 60^a which will cause

the diaphragm pouch member 54^a to be drawn upwardly from the extended end of the duct 42^a, effectively opening the latter and permitting the pressure impulses to be passed from the duct 42^a to the duct 55^a whenever the playing key 50 of the manual is operated to admit atmosphere to destroy the normal vacuum of the duct 42.

When the stop member 63^a is pulled out, to the right as illustrated, the duct 62^a is connected to the wind tension of the duct 65^a and the diaphragm pouch 54^a is collapsed against the opening of the duct 42^a, and no impulse can be transmitted from the duct 42^a to the duct 55^a.

The remaining portion of the impulse from the atmosphere admitted to the duct 42, passes along the branch duct 42^x which controls the setting of all four pipes of the harmonic series between octaves, when the first pipe of the series is caused to speak.

To bring about this result, the atmospheric impulse passes to the end of the duct 42^x and into the chamber 67^x on one side of the diaphragm pouch 68^x. Leaving the chamber 67^x, the impulse passes along the duct 69^x to a manifold 70^x having three branches to ports covered with small flap valves 71^a, 71^c, 71^f. These flap valves are located in chambers leading respectively to the ducts 59^a, 59^c, 59^f. These ducts lead respectively to the primary pneumatics 41 of the pipes A, C, and F-octave where F is the note sounded.

For each pipe which is considered the first of an harmonic series, there is provided a means for operating, at will, the first and third pipes of the series when the stop means has the proper setting. The duct 42^c, chamber 53^c, diaphragm pouch 54^c, chamber 60^c, duct 62^c, duct 55^c, duct 59^c, correspond to similar similarly numbered parts having "a" for an exponent. The same applies also for the operation of the fourth member of the harmonic series, the parts of which are designated with corresponding numerals with the exponent "f".

Similarly there is a duct 42^x, chamber 67^x, pouch pneumatic 68^x for each pipe with the necessary connections to the three other pipes of its harmonic series to sound the latter with the first pipe when desired.

It will be noted that whenever a pipe, in the main row of pipes, is made to speak, vacuum tension is placed in the power pneumatic and also in a duct 72 extending downwardly into the vacuum tension chamber 38^a. This duct 72 is connected by the duct 72' to a second power pneumatic in the second row of pipes and by the duct 72'' to a third pipe in a third row. These latter two connections are always made when a note in the first row is sounded.

If the wind chest of the second or third row has wind pressure therein the corresponding note of the second or third row will

also speak, and so on for other rows of pipes. On the opposite side of the diaphragm pouches 68^x from the chambers 67^x are chambers 60^x, which chambers are all connected together by a single duct 62^x which is controlled by a single stop member 63^x. Connections to a valve chamber 64^x are made by the ducts 66^x and 65^x which are at their other respective ends connected to the vacuum tension and wind tension chests. By moving the stop member 63^x in or out (left or right as shown) the four pipes of respective harmonic series may be connected so as to sound simultaneously when the first of the series is sounded, or be disconnected for individual control.

The parts 53^a, 54^a, 55^a, 57^a, 58^a, 59^a, 60^a, 61^a, 62^a, 63^a, 64^a, 65^a, 66^a in connection with the operation of the second member of the harmonic series, all have counterparts, those for the third member of the harmonic series having the same numbers with "c" as an exponent and those for the fourth member—one octave distant,—having the same numbers with the exponent "f."

25 In providing power for the tension means, I have combined the wind tension producing means and the vacuum tension producing means so that a single pump means is utilized to draw air from the vacuum chests.

30 In Figure 5, I have illustrated by diagrammatic showing this part of the device.

An air pump 100 is operated by a motor 101 and draws air in through the duct 102 which is connected to the main vacuum chest 38^a. The small vacuum chest V is evacuated by a tube 103 into the vacuum tension chamber 38^a.

To supply the wind pressure to the wind chests 104, 104^a, the air after it is exhausted from the vacuum chests, is sent into the chests 104, 104^a by the duct 105 and to the small wind chest W by the duct 105^a.

For the sake of clearness the pressure relief valve which keeps the tension in the vacuum chest constant and the stop devices for controlling the admission of wind pressure to the pressure wind chests, have both been omitted from the showing. As these per se do not form part of the invention and are well known in the art their illustration is not thought to be necessary.

As the vacuum devices including the primary pneumatics and relief valve are all located adjacent the vacuum chest, it will be clear that the air taken into the air pump will have the same humidity and temperature as the other air in the room where the organ is located. This air then being sent to the pressure wind chests, insures the same conditions for the pipes as they were having prior to the playing of the organ. In this way, the starting of the organ will not cause a portion of the pipes to be subjected to different air conditions than those which have not been playing. Thus the conditions in my organ start

and remain the same for all pipes throughout the period of playing.

Let us assume that the stop members 63^a, 63^c, 63^f and 63^x are all in closed or forward position (right hand position as shown on Figure 1). In this position, all of the pneumatics 54^a, 54^c, 54^f and 68^x will be collapsed, closing the tubes 42^a, 42^c, 42^f and 42^x. As the player plays in the usual manner on the manual without operating the stops to place wind in any other wind chests than the main wind chest, only those notes will play which correspond to the keys pressed. If, however, the stop is operated which admits wind pressure to the wind chest A, the corresponding pipe in the series of pipes connecting with the wind chest A will speak.

Assuming now that the player desires to play in duet, he immediately pushes in on the stop member 63^a. As already described, this causes the vacuum to lift the diaphragm 54^a and permit the connection of the duct 42^a through to the primary pneumatic 40 of the second pipe in each harmonic series of which the pipe corresponding to the key operated is the first.

If now the player desires to play the first and third pipes of each harmonic series, he will also push in the stop member 63^c. This lifts the pouch 54^c and causes the duct 42 for any note played to be connected to the third pipe of the series of which the corresponding key which has been placed is the first.

The operation of these stop devices 63^a and 63^c and their connections is independent each of the other and it is possible to operate the first and third of each series by pressing inwardly on the stop mechanism 63^c without operating the stop member 63^a.

The same also applies to the stop mechanism which is connected to the stop member 63^f which mechanism always operates a pipe one octave from the pipe corresponding to the key pressed.

If the player during the playing operation should decide that the duet or the trio caused by the operation of the stop devices 63^a and 63^c should be replaced by the quartet, temporarily, it would only be necessary to press inwardly the stop device 63^x. This operation would lift all of the pouches 68^x and then whenever a key was pressed its corresponding pipe and the succeeding three pipes of the harmonic series would also be caused to speak. This quartet setting would immediately be canceled and the pipes returned to the influence of the individual control by simply pulling out on the stop member 63^x. This operation simply places pressure in all of the chambers 60^x and cuts off communication between the ducts 42^x and 69^x. When this action occurs, the pipes return to the influence of the setting of the individual stop devices 63^a, 63^c, or 63^f or any one or two of them.

The arrangement described has been for the solo, duet, trio and quartet arrangement. It is to be understood, of course, that this arrangement may be extended as far as is desired.

While I have shown and illustrated one form of my invention in detail and have shown and described controlled mechanism to connect four pipes of a harmonic series, it is to be understood that the showing and description is merely illustrative and that the multiple connecting mechanism could be used for connecting different pipes than those enumerated and that modifications and changes may be made without departing from the spirit of the invention and within the scope of the appended claims.

Having described my invention what I claim and desire to secure by Letters Patent is:—

1. An organ having pipes, a pressure chest for providing wind tension for the speaking of the pipes, valves for controlling the connection from the chest to the pipes, a vacuum chest, power pneumatics exterior of the wind chest for operating the respective valves, connections between the power pneumatics and the vacuum chest and a primary valve for controlling the connection of the power pneumatics to the vacuum chest.

2. An organ having a pipe, a pressure chest for providing wind tension for the speaking of the pipe, a valve for controlling the connection from the chest to the pipe, a vacuum chest, a power pneumatic for operating the valve, a connection between the power pneumatic and the vacuum chest, primary valves for controlling the connections of the power pneumatics to the vacuum chest, a second pipe in the same harmonic series with the first pipe, a pneumatic and valve for causing the pipe to speak and connections for causing, at will, the second pipe to speak simultaneously with the speaking of the first pipe.

3. An organ having a pipe, a pressure chest for providing wind tension for the speaking of the pipe, a valve for controlling the connection from the chest to the pipe, a vacuum chest, a power pneumatic for operating the valve, a connection between the power pneumatic and the vacuum chest, a primary valve for controlling the connection of the power pneumatic to the vacuum chest, a plurality of pipes in the same harmonic series with the first pipe, a pneumatic and valve for each of the plurality of pipes for causing the pipe to speak and connections settable, to at will, cause any one or more of the pipes to speak simultaneously with the speaking of the first pipe.

4. An organ having a series of pipes, a valve for each pipe, pneumatic means for operating the respective valves and stop mechanism for operatively connecting together a plurality of operating pneumatic means of

pipes of chord harmonic series so as to, at will, cause a selected member of the series of that organ to speak when the first of such series is caused to speak.

5. An organ having a series of pipes, a valve for each pipe, pneumatic means for operating the respective valves and stop mechanism for operatively connecting together a plurality of operating pneumatic means of pipes of chord harmonic series so as to, at will, cause a selected member of the series of that organ to speak when the first of such series is caused to speak, said stop mechanism including separate means to, at will, cause all of the selected series to speak when the first of such series is caused to speak.

6. An organ having a series of pipes, a pressure chest for providing wind tension for the speaking of the pipes, valves for controlling the connections from the chest to the pipes, a vacuum chest, a power pneumatic for operating the valve, connections between the respective power pneumatics and the vacuum chest, a primary valve for controlling the connection between each power pneumatic and the vacuum chest, stop mechanism for operatively connecting together a plurality of power pneumatics of the pipes of harmonic series so as to, at will, cause a selected member of the harmonic series to speak when the first of such series is caused to speak and separate means to, at will, cause all of the selected harmonic series to speak when the first of such series is caused to speak.

7. An organ having a series of pipes, a pressure chest for providing wind tension for the speaking of the pipes, valves for controlling the connections from the chest to the pipes, a vacuum chest, a power pneumatic for operating the valve, connections between the respective power pneumatics and the vacuum chest, a primary valve for controlling the connection between each power pneumatic and the vacuum chest, stop mechanisms for operatively connecting a plurality of power pneumatics of the pipes together in respective harmonic series so as to, at will, cause a selected member of any of the harmonic series to speak when the first of such series is caused to speak, said stop mechanism including a pneumatic duct and cut-off means common to all of the corresponding pipes of the several harmonic series, and manually controlled means within reach of the player to operate the cut-off means to prevent or permit the operation of the power pneumatics of the selected pipes of the harmonic series with operation of the power pneumatic of the first pipe of such series.

8. An organ having a series of pipes, a pressure chest for providing wind tension for the speaking of the pipes, valves for controlling the connections from the chest to the pipes, a vacuum chest, a power pneumatic for operating the valve, connections between the

respective power pneumatics and the vacuum chest, a primary valve for controlling the connection between each power pneumatic and the vacuum chest, a stop mechanism for operatively connecting a group of power pneumatics of the pipes together in respective harmonic series so as to at will, cause the group of pipes to speak when the first pipe of such series is caused to speak, said stop mechanism including a pneumatic duct for each group of the several series and cut-off means common to all of the ducts and manually controlled means within reach of the player to operate the cut-off means to, at will, cause the operation of all of the power pneumatics of the group simultaneously with the operation of the power pneumatic of the first of the harmonic series.

9. An organ having a series of pipes and a key manual, a pressure chest for providing wind tension for the speaking of the pipes, a valve for controlling the connection from the chest to each pipe, a vacuum chest, a power pneumatic for operating each valve, connections between each of the power pneumatics and the vacuum chest, a primary valve for controlling the connection of each power pneumatic to the vacuum chest, a primary pneumatic for operating each of the primary valves, a connection between a key of the key manual and the corresponding primary pneumatic and to the primary pneumatic of a second pipe in the same harmonic series to, at will, cause the second pipe to speak when the first pipe is played.

10. An organ having a plurality of series of pipes, a pressure chest for each series for providing tension for the speaking of the pipes, valves for controlling the passage of wind tension from the pressure chest to the pipes, vacuum power pneumatics for operating the valves, a vacuum chest adjacent one of the pressure chests, primary pneumatic valves adjacent the vacuum chest and connected thereto, connections from the primary pneumatic valves to respective vacuum power pneumatics, there being one such connection to a corresponding pipe of each series.

11. An organ having a series of pipes, a pressure chest for providing wind tension for the speaking of the pipes, valves for controlling the connecting of the chest to the pipes, a vacuum chest, power pneumatics for operating the valves, connections between the power pneumatics and the vacuum chest, primary valves for controlling the connections of the power pneumatics to the vacuum chest, a plurality of pipes of an harmonic series having a common control connection, stop means under control of the player to, at will, set one or more pipes of the harmonic series to speak when one pipe of the series is made to speak and a separate stop means under control of the player, to cause all of any har-

monic series to speak when the first pipe of the series is caused to speak.

12. An organ having a series of pipes, a pressure chest for providing wind tension for the speaking of the pipes, valves for controlling the connection from the chest to the pipes, power pneumatics for operating the valves, a vacuum chest for supplying vacuum tension to the pneumatics, a pump, an inlet connection from the vacuum chest to the pump and an outlet connection extending from the pump to the pressure chamber.

13. A primary pneumatic unit for pneumatic musical instruments comprising a plurality of hingedly connected members, a valve chamber in one of the members, a valve in the chamber, a pneumatic valve lifter in one of the members, a tension duct connected to one side of the pneumatic valve lifter and a control duct connected to the other side and means for securing the non-hinged side of the hinged members together.

14. A primary pneumatic unit for pneumatic musical instruments comprising a pouch member having a chamber and a pouch on one side of the chamber, two valve members, one of the valve members having a valve chamber, a valve in the valve chamber, one of the members having a connection to a source of vacuum and extending to the space above the pouch, the three members being hinged together to insure registration of the parts when assembled and ready inspection when desirable.

In testimony whereof, I hereunto affix my signature.
